CLAIM

The ornamental design for an adjustable high bay light fixture, as shown and described.

DESCRIPTION

FIG. 1 is a top perspective view of a first embodiment of an adjustable high bay light fixture;

FIG. 2 is an enlarged view of the portion of FIG. 1 labeled as 2;

FIG. 3 is a bottom perspective view of the first embodiment thereof;

FIG. 4 is a front elevational view of the first embodiment thereof, the rear elevational view thereof being a mirror image of the front elevational view except the broken line brace feature spaced farther from the break lines as shown in the remaining views;

FIG. 5 is a top plan view of the first embodiment thereof;

FIG. 6 is a bottom plan view of the first embodiment thereof;

FIG. 7 is a right-side elevational view of the first embodiment thereof with adjustable portions shown in a first position, the left-side elevational view thereof with the adjustable portions in the first position being a mirror image of the right-side elevational view with the adjustable portions in the first position;

FIG. 8 is a right-side elevational view of the first embodiment thereof with adjustable portions shown in a second position, the left-side elevational view thereof with the adjustable portions in the second position being a mirror image of the right-side elevational view with the adjustable portions in the second position;

FIG. 9 is a right-side elevational view of the first embodiment thereof with adjustable portions shown in a third position, the left-side elevational view thereof with the adjustable portions in the third position being a mirror image of the right-side elevational view with the adjustable portions in the third position;

FIG. 10 is a top perspective view of a second embodiment of an adjustable high bay light fixture;

FIG. 11 is an enlarged view of the portion of FIG. 10 labeled as 11;

FIG. 12 is a bottom perspective view of the second embodiment thereof;

(Continued)

FIG. 13 is a front elevational view of the second embodiment thereof, the rear elevational view thereof being a mirror image of the front elevational view;

FIG. 14 is a top plan view of the second embodiment thereof;

FIG. 15 is a bottom plan view of the second embodiment thereof;

FIG. 16 is a right-side elevational view of the second embodiment thereof with adjustable portions shown in a first position, the left-side elevational view thereof with the adjustable portions in the first position being a mirror image of the right-side elevational view with the adjustable portions in the first position;

FIG. 17 is a right-side elevational view of the second embodiment thereof with adjustable portions shown in a second position, the left-side elevational view thereof with the adjustable portions in the second position being a mirror image of the right-side elevational view with the adjustable portions in the second position; and,

FIG. 18 is a right-side elevational view of the second embodiment thereof with adjustable portions shown in a third position, the left-side elevational view thereof with the adjustable portions in the third position being a mirror image of the right-side elevational view with the adjustable portions in the third position.

The broken lines shown in the drawings are included for the purpose of illustrating portions of the adjustable high bay light fixture that form no part of the claimed design. The first embodiment depicted by FIGS. 1-9 is shown with a symbolic break in the length of the design. The break lines, as

well as any portion of the article between the break lines, form no part of the claimed design.
